DUST GUARD

Donald D. Bryant, Huntington, W. Va.

Application August 13, 1945, Serial No. 610,590

19 Claims. (Cl. 286—6)

1

This invention is a novel dustguard for the journal box housings as used in a freight car, a passenger car, and locomotive trucks and tenders, but may obviously be used in other types of journals, the present invention being an improvement upon the dustguard shown in my copending application, Serial No. 548,835, filed August 10, 1944, now Patent No. 2,391,121, issued December 18, 1945.

The principal objects of the present invention are to provide novel improvements in the construction of the dustguard rack, and the mounting therein of the flexible dustguard band; also novel improvements in the dustguard band per se, which will facilitate manufacture and improve the operation of the dustguard.

I will explain the invention with reference to the accompanying drawings which illustrate several practical embodiments thereof, to enable others familiar with the art to adopt and use the same; and will summarize in the claims the novel features of construction, and novel combinations of parts, for which protection is desired.

In said drawings:

Figure 1 is a longitudinal section through a typical journal box housing provided with my novel dustguard rack housed in the customary cavity pocket which is cast at the inner end of the housing.

Fig. 2 is a transverse section of the line 2—2, Fig. 1.

Fig. 3 is an enlarged transverse section on the line 3—3, Fig. 1.

Fig. 4 is a section on the line 4—4, Fig. 3.

Fig. 5 is a plan view of one form of dustguard band, detached.

Fig. 6 is an enlarged section on the line 6—6, Fig. 5.

Fig. 7 is an extended side elevation of a modified form of dustguard band.

Fig. 8 is an extended side elevation of a further modified form of dustguard band.

Fig. 9 is a top plan view of dustband shown in Fig. 8.

Fig. 10 is a transverse section, similar to Fig. 3, but showing a modified construction.

Fig. 11 is a vertical section on the line 11—11, Fig. 10.

As shown in Figs. 1—4 inclusive, the journal J of the railway or other truck is entered in the normal manner in the journal box B of usual construction, the same containing packing P saturated with a lubricant, the particular form of journal box B forming no part of my present invention. Such journal boxes B are customarily

2

provided at their inner ends with a cavity or pocket B' for the reception of a dustguard, usually of rigid construction, formed of layers of plywood or fiber, riveted or stapled together.

5 In place of the usual rigid dustguard, however, above mentioned, I provide a dustguard rack of size and dimensions to fit within the cavity B' which is ordinarily open at its top, said rack being designated generally by the reference character 1 and making a snug fit within cavity B', as shown more particularly in Figs. 3 and 4.

Said dustguard rack 1 preferably comprises a box-like structure formed of spaced parallel plates 1a—1b of metal, plastic or other suitable 15 material and of shape and size conforming with the cross sectional area of cavity B', the plates 1a, 1b being secured together in any desired manner. Rack 1 has a peripheral plate 1c closing the sides and bottom of the rack, and plates 1a, 1b 20 are provided with journal receiving circular openings 1e of larger diameter than the journal J through which openings the journal extends. The edges of the openings 1e in the plates 1a, 1b are preferably inturned as at 1x, for the purpose 25 hereafter described. The upper edges of plates 1a, 1b are out-turned as at 1f (Figs. 3—4), said out-turned portions overlying the top of cavity B', and a closure plate 3 having guide slots at its side edges is slipped over the out-turned flanges 30 1f and forms a removable top for the filler rack 1 to exclude dust and dirt from entering between the plates 1a, 1b.

Extending for approximately half the width of the top of rack 1 from one side thereof is a flange or plate 1g closing said half of the top of 35 the rack, but leaving an opening 1j at the top of the rack coextensive with the other half thereof, said opening being provided for the endwise insertion and removal of the flexible dustguard band 10 therethrough as hereinafter described.

A fixed support is provided near the top of the rack 1 adjacent the inner end of top wall 1g, said support being formed in any desired manner and serving as an anchor for the fixed end of a flexible 45 metallic band. As shown, the support comprises a tongue 1k preferably struck out of the metal of one of the side plates 1a, 1b, the tongue extending inwardly of the rack, and the fixed end 4a of a flexible metallic band 4 is anchored on said 50 support 1k in any desired manner. The band 4 beyond the support 1k is bent downwardly over the inner end thereof and is curved on an arc concentric with the openings 1e, the band continuing around on said arc to a point 4b spaced 55 from the fixed end 4a of the band a distance suffi-

cient to permit endwise insertion and removal of the dustguard band 10 in a tangential direction through the inner portion of the opening 1j. The flexible band 4 is preferably formed of steel and is of width slightly less than the distance between plates 1a, 1b of the rack so as to be readily expansible and contractible therein, said band, however, being of greater width than the space between the inturned flanges 1x at the openings 1e of the rack, the flanges 1x preventing removal of the band 4 from the rack through the openings 1e.

In order to guide and support the outer free end of the flexible band 4, a block or boxlike structure 5 is provided within the upper corner of the rack within the opening 1j, the upper edge 5a of block 5 forming a continuation of the top plate 1g of the rack at the opposite side of opening 1j; and said block 5 has an inclined face 5b disposed substantially tangent to the journal J at a point below the support 1k of the fixed end of band 4. Block 5 may be mounted in the rack 1 in any desired manner so as to be fixedly or removably positioned therein.

Cover plate 3 is provided with a slot 3a in its inner end of length to embrace that of the opening 1j between the walls 1g and 5a, said cover 3 also having a hand grip 3b on its outer end whereby the plate may be shifted upon the outturned flanges 1f of the rack.

Block 5 is further provided with an arcuate face 5c containing a recess 5e housing a spring 6, one end of which is secured to a cross pin 7 within recess 5e adjacent its upper end, the other end of the spring 6 being fixed as at 6a to an outwardly projecting lug 4c on the flexible band 4 within recess 5e. Thus, recess 5e houses the spring 6 which yieldably contracts the band 4 by urging the outer free end 4b thereof in the direction of the fixed support 1k for the fixed end 4a of the band. In order to maintain the outer end 4b of flexible band 4 in its normal relative position within rack 1 in event spring 6 or its connections with the band or block 5 should break, a safety wire 8 is provided passing through an opening in the recess 5e of block 5 and having one end fixed to the lug 4c and its other end fixed to a pin 9. Thus, if spring 6 should become unfastened or break, the wire 8 will limit the movement of the outer free end 4b of the band 4 and prevent same from becoming unduly flexed from its proper position, the wire 8, however, normally having no effect upon the action of spring 6 in contracting the band 4. Instead of utilizing a block or boxlike structure 5 the arcuate grooved portion 5e for spring 6 may be formed by a tongue inturned from one of the side walls 1a, 1b of the rack.

One form of dustguard band usable in the above assembly is illustrated in Figures 5-6, the same consisting of a length of yieldable and flexible packing material which may be woven, moulded, pressed, cast, knit, or may be impregnated so as to contain rubber or rubber composition, to withstand rugged wear, friction and oil saturation. Band 10 is made from material commonly known as packing material commonly used to make sealed joints and to keep substances such as liquid, solids, gases, steam, or vapors from penetrating beyond a point fixed by the packing seal. As shown in Fig. 5, the dustguard band 10 is preferably formed of circular shape corresponding generally with the diameter of the journal J, the band 10 being of thickness to fit between the flanges 1x (Fig. 4) at the openings 1e so that its

inner face will squarely contact the journal J, as shown more particularly in Fig. 4, while its outer face will squarely contact the flexible metallic band 4 which is mounted to yieldably contract the dustguard band 10 around the journal J. The band 10 should have sufficient lateral play in the rack so that it will not bind or otherwise be cramped or prevented from a free sliding endwise movement. The band 10 should preferably be constructed as one continuous piece, with flat sides and faces. Band 10 is provided with a handle portion 10a which is substantially tangent to said end of the band, handle portion 10a being adapted to project through the opening 1j and through the end slot 3a in the cover plate 3, and to project above the cover plate 3, as clearly shown in Fig. 3. In the sides of handle portion 10b aligned with the slot 3a in cover plate 3 are grooves 10x (Fig. 3) adapted to receive the edges of the slot 3a in cover plate 3 when the cover is in position shown in Fig. 3 to prevent endwise withdrawal of the dustguard band 10 from the rack until cover plate 3 is pulled off the end of the rack 1. Preferably a pull 11 is provided on the projecting end of handle portion 10b to facilitate endwise withdrawal of the band 10 from the rack 1. The free end of the band 10 is reduced in thickness as at 10c (Fig. 6) adjacent the base of the handle portion 10b so that when the packing is inserted in the rack the end 10c will overlap at correspondingly thinned portion 10d with the body of the band 10 adjacent the handle portion 10a and thereby form a continuous unbroken surface around the entire circumference of journal J. The reduced sections 10c, 10d of band 10 overlap to form an oil seal; and preferably the reduced portion 10d is of sufficient length to extend beyond the outer end of the mating portion 10c to provide a space permitting take-up for wear at the inner face of the band 10. In my band 10 the trailing end 10c is reduced in thickness to approximately half of the width of the band to fit in the slot or groove 10d in the handle end of the band also reduced in thickness to approximately one-half of the band's actual thickness, so that when encircling the journal J and held in place by the metal band 4, the reduced end 10c is made to slide in and along the slot or groove 10d at the handle end, the two reduced portions 10c, 10d thus contacting to form a circular seal around the journal J, the two reduced portions 10c, 10d together building up the band to its original thickness at said overlapping portions. Thus by this slide or slip fit an adjustable circular sealing fit is maintained. The slot or groove 10d near the handle 10a is cut or moulded to the correct angle so that when the band is entered in the rack 1 the trailing end enters into and slides along this reduced portion 10d making a perfect seal.

By the above construction, when the dustguard band 10 is inserted endwise into the filler rack 1 through the opening 1j, tangentially of journal J, the leading end 10c of the band 10 will contact the metallic flexible band 4 and will be guided thereby around the journal J and will be held by band 4 contracted around the journal. The metallic band 4 will adjust itself around the dustguard 10 and will serve as a protector for the band 10. The dustguard band 10 is pushed inwardly of the rack tangentially of the journal J through the opening 1j until the end 10c overlaps the reduced portion 10d of the band in which position the grooves 10x will lie opposite the sides of the slot 3a of the cover plate 3, whereupon the

cover 3 may be pushed inwardly into the position shown in Fig. 3 with the sides of slot 3a entered in the grooves 10x. The dustguard band 10 will thereby be securely locked in the rack 1 and cannot be pulled outwardly until the cover plate 3 has been pulled endwise off of the rack 1.

In place of the dustguard band 10 shown in Figs. 5-6, a modified band, shown in Fig. 7, may be used, same having a stiffening wire 10w extending entirely through the length of the band 10 from end to end, the band 10 being shown expanded in Fig. 7.

Also the band 10 may be further modified, as shown in Fig. 8, in which a stiffening wire 10w extends through the handle portion 10b only, the wire 10w being omitted throughout the remaining portion of the length of the band. However, throughout the major portion of the length of band 10 from the handle 10b to the thinned top portion 10c is provided on each side wall with corrugations 10p to facilitate flexing of the band 10 when being inserted and removed from the rack.

The rack 1 and its parts are thus completely covered and protected by cavity B' in the journal box housing B. When assembled and placed in the dustguard cavity B' it makes a solid seal between the opening in the wheel side of the journal box housing B and the interior of the journal box which contains the packing P, the journal bearing surface, and the burnished surface of the journal upon which the bearing rides. The dustguard excludes foreign material such as metal, dirt, sand, grit or other debris from entering the packing or lubricant which would cause a hot-box, journal box failure or would contribute to train delays, accidents or damage to material or equipment. My dustguard band not only excludes foreign matter from entering the journal box but also prevents by its self-sealing adjustable action, the oil within the journal box from leaking out of the dustguard side of the journal box housing, thus retaining therein the free or loose oil, which otherwise would be lost due to the action of a car or train in motion and the movement of axle in said journal box, which would cause the oil to flow or splash or run along the journal or bearing surface and thence out of the journal box housing. My band 10 also keeps the packing P from being pushed past the fillet on the burnished surface of the journal (this fillet being the lateral stop for the journal brass). In event the packing P is pushed past the fillet it would then be disposed on top of the dustguard surface of the axle; and if it extends through the journal box housing at this point it will act as a natural drain through wick action and draw the free or loose oil out between the wheel and the journal box to the ground. It is only necessary to look at the plates or face sides of passing wheels on the average freight car to see that a larger percentage of these wheel plates are covered with an oil film which is positive proof of the oil escaping from the journal box due to lack of seal to retain it, thus wasting many thousands of gallons of oil daily. My dustguard will also prevent the loss of oil to a great extent when applied to coal cars which are dumped by being turned mechanically over on their sides or ends.

In the modification shown in Figs. 10 and 11, a simplified construction is illustrated in which the like parts are similarly numbered. In this construction, however, the rack plate 1a is flanged as at 1c to form the side and bottom edges of the rack, the outer end of the flange 1c being inset

as at 1z, Fig. 11, to receive similar short flange 1y formed integrally with the rack plate 1b, the flanges 1b, 1c being coextensive with the two ends and bottom edges of the rack. The upper ends of the walls 1a, 1b of the rack are outturned as at 1f in the same manner shown in the preceding figures.

In this modification, an angularly inclined wall 15 having a flange 15a is welded or otherwise secured to the wall 1b of the rack, the same extending from one edge of the opening 1j in the top of the rack downwardly and substantially tangent to the flexible dustguard band 10; while a second inclined wall 16 extends from a point adjacent the opposite end of opening 1j and slopes downwardly substantially tangent to the journal J within the rack, the space between the walls 15 and 16 being slightly greater than the height or depth of the dustguard band 10.

20 A cover plate 1g extends over the upper end of the rack from the opening 1j to the adjacent side of the rack and may be permanently secured thereto, the same preferably being provided with downwardly and inturned flanges underlying the outturned flanges 1f of the walls 1a, 1b of the rack, in the manner shown in Fig. 11.

25 In this modification a top plate 1w extends from the opposite end of opening 1j to the adjacent side of the rack, and is provided with downwardly and inturned flanges 1v underlying the outturned flanges 1f of the walls 1a, 1b of the rack, as shown in Fig. 10, the inner end of top plate 1w extending somewhat inwardly across the opening 1j beyond the adjacent end of the wall 16, forming a 30 lip adapted to be engaged by a notch 10y in the adjacent edge of the handle portion 10b of dustguard band 10, to maintain the dustguard band 10 locked in its innermost position when inserted in the rack in the manner shown in Fig. 10.

40 When, however, it is desired to remove the dustguard band 10 from the rack, it is merely necessary to flex the outer projecting end of handle portion 10b upwardly sufficiently to free the lower edge of notch 10y from the underside of the lip of 45 top plate 1w, whereupon the dustguard band may be readily removed by endwise pull from the rack.

50 By the above construction dust and dirt are prevented from entering the interior of the rack, since the handle portion 10b completely fills the opening 1j in the top of the rack; and no movable or shiftable cover is necessary in order to lock the dustguard band in operative position within the rack.

55 As shown in Fig. 10, an arcuate wall 17 extends from the lower end of the inclined wall 16, and is spaced somewhat from the outer periphery of dustguard band 10, said wall 17 having a flange 17a which is spotwelded or the like to the inner face of the wall 1b of the rack. 60 Arcuate wall 17 has a longitudinal slot 18 therein, for the purpose hereinafter described. If desired, the walls 15, 16 and 17 may be struck out of the metal of one or both walls of the rack, or formed in any other desired manner.

65 In this modification it is not necessary to provide the inturned flanges 1x (shown in Fig. 3) at the circular openings 1e in the rack walls 1a, 1b through which the journal J passes, since both ends of the flexible band 4 are securely held within the rack, thus preventing the flexible band 4 from being withdrawn through the openings 1e when the rack is removed from the pocket in the journal box housing. As shown, one end of the flexible band 4 is flanged over as at 4p over 70 the top of the inclined wall 15 at one end of

opening 17, to fix said end of the flexible band 4, the band 4 passing around the periphery of dustguard band 10 with its free end disposed between the band 10 and the arcuate wall 17. The free end of band 4 carries a post 19 (Fig. 10) of sufficient length to extend through the slot 18 in arcuate wall 17, the same having a head or washer 19a on its outer end; and a spring 20 has one end engaged with the post 19 and its other end secured by welding or hooking to a fixed portion of the rack adjacent wall 16 the spring 20 normally contracting the flexible band 4 around the dustguard band 10 and the journal, the length of post 19 permitting the end of flexible band 4 to shift radially inwardly or outwardly with respect to the journal, and the post 19 being sufficiently long to allow free play of the free end of the flexible band 4 in this respect while preventing the band 4 from being withdrawn from its relative position within the rack shown in Figure 10.

I do not limit my invention to the exact forms shown in the drawings, for obviously changes may be made therein within the scope of the claims.

I claim:

1. In combination with a journal, a journal box having a cavity pocket therein; a filler rack removably positioned in said pocket and having a bore therethrough through which said journal extends, said rack having an opening in its top offset from the axis of the journal; a top plate for said rack having a lip overlying the opening; and a flexible dustguard band within the rack encircling the journal and having one end extending through the slot in the closure plate and having a notch underlying said lip.

2. In a combination as set forth in claim 1, said top plate having a portion slidably mounted upon said rack and provided with a slot overlying said opening said slot being disposed at the inner end of the plate; and said notch in the dustguard band comprising a groove in the side of the band receiving the adjacent side wall of the slot to prevent withdrawal of the dust guard band until the top plate is removed.

3. In a combination as set forth in claim 1, said top plate being fixedly secured to the rack and having a portion extending over one end of the opening; and said notch being formed in the adjacent face of the band to prevent withdrawal of the dustguard band until the band is flexed to disengage the notch from said lip.

4. In a combination as set forth in claim 1, said dustguard band comprising a split loop of flexible packing material conforming substantially with the curvature of the journal, said loop having one end extending substantially tangentially of the journal through said opening to form the locked end; the opposite end being reduced in width and engaging when positioned in the rack a correspondingly reduced portion in the band adjacent the inner end of the tangential portion, whereby the band will form an unbroken seal around the journal, the reduced portions being of sufficient extent to permit relative shifting of the ends of the loop to compensate for wear.

5. In a combination as set forth in claim 1, said dustguard band comprising a split loop of flexible packing material conforming substantially with the curvature of the journal, a stiffening wire extending longitudinally through the dustguard, said loop having one end extending substantially tangentially of the journal

through said opening to form the locked end; the opposite end being reduced in width and engaging when positioned in the rack a correspondingly reduced portion in the band adjacent the inner end of the tangential portion, whereby the band will form an unbroken seal around the journal, the reduced portions being of sufficient extent to permit relative shifting of the ends of the loop to compensate for wear.

10. 6. In a combination as set forth in claim 1, said dustguard band comprising a split loop of flexible packing material conforming substantially with the curvature of the journal, said loop having one end extending substantially tangentially of the journal through said opening to form the locked end; the opposite end being reduced in width and engaging when positioned in the rack a correspondingly reduced portion in the band adjacent the inner end of the tangential portion, whereby the band will form an unbroken seal around the journal, the reduced portions being of sufficient extent to permit relative shifting of the ends of the loop to compensate for wear; a stiffening wire extending throughout the length of the tangential portion; and the side walls of the remaining portion of the loop between the reduced portions being corrugated to facilitate bending.

30. 7. In combination with a journal, a journal box having a cavity pocket therein; a filler rack removably positioned in said pocket and having a bore therethrough through which said journal extends; said rack having an opening in its top offset from the axis of the journal; a top plate for said rack having a lip overlying said opening; a yieldable band within the rack around and spaced from the journal and having its ends secured at opposite sides of the opening; and a flexible dustguard band within the rack encircling the journal within the yieldable band; said dustguard band being insertable in and removable from the rack by endwise movement through said opening, and the trailing end thereof having a notch underlying the lip when inserted therein.

35. 8. In a combination as set forth in claim 7, said top plate having a portion slidably mounted upon said rack and provided with a slot overlying said opening said slot being disposed at the inner end of the plate; and said notch in the dustguard band comprising a groove in the side of the band receiving the adjacent side wall of the slot to prevent withdrawal of the dustguard band until the top plate is removed.

40. 9. In a combination as set forth in claim 7, said top plate being fixedly secured to the rack and having a portion extending over one end of the opening; and said notch being formed in the adjacent face of the band to prevent withdrawal of the dustguard band until the band is flexed to disengage the notch from said lip.

55. 10. In a combination as set forth in claim 7, said dustguard band comprising a split loop of flexible packing material conforming substantially with the curvature of the journal, said loop having one end extending substantially tangentially of the journal through said opening to form the locked end; the opposite end being reduced in width and engaging when positioned in the rack a corresponding reduced portion in the band adjacent the inner end of the tangential portion, whereby the band will form an unbroken seal around the journal, the reduced portions being of sufficient extent to permit relative shifting of the ends of the loop to compensate for wear.

11. In a combination as set forth in claim 7, said dustguard band comprising a split loop of flexible packing material conforming substantially with the curvature of the journal, a stiffening wire extending longitudinally through the dustguard, said loop having one end extending substantially tangentially of the journal through said opening to form the locked end; the opposite end being reduced in width and engaging when positioned in the rack a correspondingly reduced portion in the band adjacent the inner end of the tangential portion, whereby the band will form an unbroken seal around the journal, the reduced portions being of sufficient extent to permit relative shifting of the ends of the loop to compensate for wear.

12. In a combination as set forth in claim 7, said dustguard band comprising a split loop of flexible packing material conforming substantially with the curvature of the journal, said loop having one end extending substantially tangentially of the journal through said opening to form the locked end; the opposite end being reduced in width and engaging when positioned in the rack a corresponding reduced portion in the band adjacent the inner end of the tangential portion, whereby the band will form an unbroken seal around the journal, the reduced portions being of sufficient extent to permit relative shifting of the ends of the loop to compensate for wear; a stiffening wire extending throughout the length of the tangential portion; and the side walls of the remaining portion of the loop between the reduced portions being corrugated to facilitate bending.

13. In a combination as set forth in claim 7, the end of the flexible band adjacent the trailing end of the dustguard band being anchored in the rack; and the other end of the flexible band engaging an arcuate guide adjacent the leading end of the dustguard band; said guide having a recess; and means in said recess engaging the guide and flexible band for yieldably contracting the flexible band around the dustguard band.

14. In a combination as set forth in claim 7, the end of the flexible band adjacent the trailing end of the dustguard band being anchored in the rack; and the other end of the flexible band engaging an arcuate guide adjacent the leading end of the dustguard band; said guide having a recess; a spring in said recess having one end secured to the guide and the other end secured to the flexible band for yieldably contracting the flexible band around the dustguard band; and a normally flexed safety cord connecting the guide and adjacent end of the flexible band to hold the flexible band in relative position around the dustguard band in event the spring should break.

15. In a combination as set forth in claim 7, the end of the flexible band adjacent the trailing end of the dustguard band being anchored in the rack; and the other end of the flexible band un-

derlying an arcuate guide adjacent the leading end of the dustguard band; said guide having a slot; a post on the flexible band extending through said slot; and a spring having one end secured to said post and its other end secured to said post for yieldably contracting the flexible band around the dust guard band while permitting the adjacent end of the flexible band to shift radially with respect to the journal.

16. A dustguard band for journal box housings or the like comprising a split loop of flexible packing material having one end extending substantially tangentially to form a handle end; the opposite end being reduced in width and engaging a correspondingly reduced portion in the band adjacent the inner end of the handle portion, the reduced portions being of sufficient extent to permit relative shifting of the ends of the loop.

17. In a band as set forth in claim 16, a stiffening wire extending throughout the tangential portion; and the side walls of the remaining portion of the band between the reduced portions being corrugated to facilitate bending.

18. In combination with a journal, a journal box having a cavity pocket therein; a filler rack removably positioned in said pocket and having a bore therethrough through which said journal extends; said rack having an opening in its top offset from the axis of the journal; a yieldable band within the rack around and spaced from the journal and having its ends secured at opposite sides of the opening; the flexible band having one end anchored in the rack, and the other end engaging an arcuate guide, said guide having a recess; a spring in said recess having one end secured to the guide and the other end secured to the flexible band for yieldably contracting the flexible band around the journal; and a flexible dustguard band within the rack encircling the journal within the yieldable band; said dustguard band being insertable in and removable from the rack by endwise movement through said opening, and means for locking the dustguard band in the rack.

19. In a combination as set forth in claim 18, a normally flexed safety cord connecting the guide and adjacent end of the flexible band to hold the flexible band in relative position around the dustguard band in event the spring should break.

DONALD D. BRYANT.
